BUILDING STRUCTURE

Thomas Carvel, Yonkers, N. Y.

Application December 10, 1952, Serial No. 22,616

Term of patent 14 years

(Cl. D13—1)

To all whom it may concern:

Be it known that I, Thomas Carvel, a citizen of the United States, residing at Yonkers, in the county of Westchester and State of New York, have invented a new, original, and ornamental Design for a Building Structure, of which the following is a specification, reference being had to the accompanying drawing, forming part thereof.

Fig. 1 is a front elevational view of a building structure, showing my new design;

Fig. 2 is a rear elevational view;

Fig. 3 is a side elevational view; and

Fig. 4 is a side elevational view, opposite that shown in Fig. 3.

I claim:

The ornamental design for a building structure, as shown and described.

THOMAS CARVEL.
